(57) **CLAIM**

The ornamental design of a water ride, as shown and described.

DESCRIPTION

FIG. 1 is a perspective view of a water ride showing our new design;

FIG. 2 is a cross sectional view taken on line 2-2 of FIG. 1;

FIG. 3 is a top plan view of FIG. 1;

FIG. 4 is a bottom plan view of FIG. 1;

FIG. 5 is a left side view of FIG. 1;

FIG. 6 is a right side view of FIG. 1;

FIG. 7 is an end view of FIG. 1; and,

FIG. 8 is an opposite end view of FIG. 7.
